UNITED STATES PATENT OFFICE.

HENRY ELIAS HOKE, OF CHAMBERSBURG, PENNSYLVANIA.

CAR-DOOR FASTENER.

SPECIFICATION forming part of Letters Patent No. 427,419, dated May 6, 1890.

Application filed January 21, 1890. Serial No. 337,614. (No model.)

To all whom it may concern:

Be it known that I, HENRY ELIAS HOKE, a citizen of the United States, residing at Chambersburg, in the county of Franklin and State 5 of Pennsylvania, have invented certain new and useful Improvements in Fastening Devices for the Doors of Freight-Cars; and I do hereby declare the following to be a full, clear, and exact description of the invention, reference being had to the accompanying drawings, which form part of this specification.

My invention has relation to fastening devices for the doors of freight-cars, and has for its object the provision of a novel and effectual fastening device which will operate to 15 press the door firmly against the jamb and at the same time against the side of the car, and hold it securely in such position.

My present invention is an improvement 20 upon the invention described and shown in Letters Patent of the United States No. 311,761, granted to me February 3, 1885. In the said Letters Patent I have shown and described a fastening device for car-doors comprising a lever pivoted to the car-door by means of a curved pintle or hinge-link passing through a lug on the end of the lever and the latter being formed with a beveled lug and a curved toe on its under side that engaged with a suitable socket set in the side 25 of the car when the door was closed and served to force the door against its jamb and against the side of the car.

In carrying my present invention into effect I employ a pivoted lever having upon its end a bent toe beveled on the sides that takes into a socket set in the side of the car. This lever I secure to the car-door by means of a link carrying a pintle on one end that passes 30 through a lug on the end of the lever and a curved pintle that projects from a plate secured at the edge of the car-door and passes through a hole in the link.

Referring to the accompanying drawings, 35 Figure 1 is a side elevation of a portion of a car and car-door having my improved fastening device in position thereon. Fig. 2 is a vertical sectional view of the same, the fastening device being in its closed position; Fig. 40 3, a similar view to Fig. 2, showing the fastening device about to be closed; and Fig. 4, a similar view to Fig. 3, but with the fastening

lever thrown out of engagement with its socket and down out of the way.

In the said drawings similar letters of reference indicate like parts.

A designates the body of the car, and B the sliding door of the same. To the door, just at the back edge of the same, is secured a plate C by bolts *c c c*, and projecting from 55 said plate is a curved pintle C', that bends up and around until its upper end reaches the edge of the door.

D designates a link, which is swung upon the pintle C' and has a laterally-projecting 60 pin *d*, that passes through a lug *e* on a lever E and is held in position by a pin *d'*, passing through the pin *d* on the outside of the lug.

The lever E is formed with a toe F, that is beveled off on each side and takes into a 70 socket G, set into the side of the car. The socket G is beveled interiorly on each side, and the edge G' of said socket that the toe F engages with is rounded underneath, so that as the lever E is brought down to its fully-75 closed position the toe, acting on the rounded portion of the edge G', will gradually bring the door up tight against the side of the car.

The lever E, it will be observed, when in its closed position, lies alongside and parallel 80 with the back edge of the door, and is held in this position by means of a T-shaped latch piece or plate H, which is formed with holes *h h'* at the extremities of its arms, and is pivoted at *i* to a plate I, which is bolted to the 85 car-door near the edge of the same.

In one position of the latch piece or plate H the lever E may be freely lowered or raised; but when it is desired to lock the lever the latch-piece is swung around into the position 90 shown in Fig. 1, so that the arm which has the hole *h'* will project over the end of the lever, and the hasp of a padlock K is passed through the hole *h'*, and the padlock being locked the lever will be kept closed. The 95 object of the holes *h h* in the other ends of the latch piece or plate H is to provide means for the attachment of a seal, the wire to which the seal is attached being passed through one of the holes *h h* and through a hole *e'* in the 100 end of the lever E.

The parts being constructed and arranged as above described, are operated in the following manner: The door being closed and

fastened, as shown in Figs. 1 and 2, to open the same the padlock is first removed from the latch-piece H and the latter is swung around out of the way. The lower end of the lever E is then drawn out from the edge of the door a few inches, its weight causing it to drop down, so that the toe F will come out of the socket G. The lever is then allowed to drop, when it will assume the position shown in Fig. 4—that is, it will hang alongside of the edge of the door with the toe F out of engagement with the socket G—and in this position the lever E will remain while the door is being opened and closed without danger of contacting with the side of the car or with any extraneous object. To close the door, the lower end of the lever E is drawn out a very short distance from the edge of the door, just sufficient to allow the toe F to be pushed up into the socket G, as is shown in Fig. 3 of the drawings. The lower end of the lever is now pressed in until it is flush with the surface of the door, and the latch-piece H is then turned around until one of its arms is over the end of the lever, which is thereby held in its closed position. A padlock may now be attached to the latch, its hasp being passed through the hole h', as before described, or if it is desired to seal the fastener the wire to which the seal is secured is passed through one of the holes h and through the hole in the end of the lever E, and the seal attached to the ends of the wire.

The peculiar construction and arrangement of the several parts are such that it requires but a very small amount of motion of the le-

ver E in either fastening or unfastening and permits of the door being easily and readily secured when it has warped or sprung a very considerable distance, as it may do. The lever being suspended from the hook by a loose ring or link, it will adjust itself to the angle of the socket G, no matter how much the socket may be thrown out of its normal position by the sinking or warping of the car. 45

The whole device is reasonably cheap and simple in construction and forms a most efficient fastening for car or other sliding doors.

Having described my invention, I claim—

1. In a car-door fastening device, the combination, with a lever E, having the toe F and the socket G, with which said toe engages, of the plate C, secured to the door, the curved pintle C', projecting from said plate, and the link D, swung upon said pintle and pivoted to the said lever, substantially as described. 50

2. In a fastening device for car-doors, the combination, with plate C, secured to the door, and curved pintle C', projecting from said plate, of link D, hung upon said pintle and having a laterally-projecting pin d, the lever E, having a lug e, through which said pin passes, and a toe F, adapted to engage with a socket G, substantially as described. 55

In testimony that I claim the foregoing I have hereunto set my hand this 16th day of January, 1890. 60

HENRY ELIAS HOKE.
